UNITED STATES PATENT OFFICE.

GUSTAVE FRANKEL, OF CHICAGO, ILLINOIS.

RECEPTACLE FOR CONNECTING PLUGS.

Application filed September 22, 1921. Serial No. 502,554.

My invention relates to a new and improved receptacle for connecting plugs. The large growth in the use of electrical apparatus of various kinds has made it desirable to provide receptacles for connecting plugs whereby current can be drawn off to vacuum cleaners, lamps or the like, and it has been customary to frequently place these receptacles in the walls of the room where it is desired to use these plugs.

The construction of these receptacles has hitherto been expensive so that a large portion of the community has still continued to use the sockets provided for the insertion of incandescent lamps.

According to my invention, a very simple and attractive looking and cheap construction is provided for these receptacles. Another object of my invention is to provide a receptacle whereby a plug can be connected in series or in tandem. Other objects of my invention will be set forth in the following description and drawings which illustrate a preferred embodiment thereof.

Fig. 1 is a top view.

Fig. 2 is a bottom view.

Fig. 3 is a perspective view.

Fig. 4 is a detail sectional view.

Fig. 5 is an inner view of one of the receptacle elements showing the contact spring in position.

Fig. 6 is the same as Fig. 5 but showing the contact spring omitted.

Fig. 7 is a view similar to Fig. 5 but showing a different type of contact spring, the construction of said receptacle member being also somewhat different.

Fig. 8 shows the receptacle of Fig. 7 without the contact spring.

Fig. 9 is a perspective view of the contact spring illustrated in Fig. 5.

Fig. 10 is a perspective view of the contact spring illustrated in Fig. 7.

A metal plate 1 has two outer openings 2 and 3 provided therein, whereby the said metal plate can be secured wherever desired.

The said metal plate 1 is also provided with two openings 4' which may be of any desired contour. These openings 4' are preferably provided by means of stamping out tongues 5 from the body of the plate 1, so that these tongues 5 can act as supports for the receptacle members to be later described. Each receptacle for the plugs is made up of two like receptacle members made of fiber or some other suitable insulating material

that can be molded or otherwise suitably shaped. These receptacle members may be identical in construction, so that each receptacle consists of two identical and equal members 4.

As seen more clearly in Fig. 6, each receptacle member 4 is provided with a flange 6 whereby it is held in position when two receptacle members are assembled as shown in Fig. 4 for example, when they may be connected by means of the bolt 7 which passes through perforations 8 in the receptacle members.

Each receptacle member is provided with two vertical grooves 9 separated by an intermediate bridge portion 10 having lateral projections 11, the vertical grooves 9 being provided with arcuate extensions 12 adjacent the lateral extensions 11. As shown in Fig. 6, the perforations 8 pass through said longitudinal bridge members 10, so that the bolt 7 passes through the said longitudinal bridge members.

It can be seen that the outer contour of each receptacle member is symmetrical with respect to the median line of the bridge 10, so that two receptacle members can be easily assembled.

The contact springs 12 as shown in Fig. 9 may be of any ordinary construction and they are preferably made of resilient metal. Each contact spring 12 is provided with a blade having a downturned projection 14 and it has an arcuate base 15 provided with a perforation 16. The parts are assembled as shown in Fig. 5. The curved and laterally bent projection of each contact spring 12 fits within the correspondingly recessed portion of the receptacle so that each contact blade is firmly held in position by means of said corresponding contours. Each contact spring 12 is provided with a screw 17 by means of which the conductor wires may be connected to said contact members 12.

The portion of each receptacle member adjacent the projection 11 may be called the base portion, and it will be noted that each receptacle member has an open base portion, whereby the assembly of the parts, inspection, repair, etc., are facilitated.

In the type of receptacle shown in the upper part of Fig. 3, it is only possible to insert the attachment plug 18 having a head made of insulating material and having the ordinary contact blades 19, in one way.

It is to be understood that the contact blades 19 contact with the receptacle blades, when the plug is inserted.

Either the plug 18 or the plug 20 may be inserted into the receptacle shown in the lower part of Fig. 3, because of the special construction of the contact blades illustrated in Fig. 10.

The contact blades illustrated in Fig. 10 have base portions 21 and they have two branches 22 and 23 of substantially the same construction as before mentioned, located substantially at right angles to each other. Fig. 2 shows the manner in which the bases 15 of the receptacle blades are held against turning, and are firmly secured in position.

It is obvious that the complete receptacle unit consists only of a metal plate and like receptacle members and like contact blades, 20 so that the entire device may be made with a minimum number of parts, operations and with minimum labor.

I have shown a preferred embodiment of my invention, but I do not wish to be limited thereto as numerous changes and omissions can be made without departing from its spirit.

Of course, it is obvious that instead of separately forming the metal plate 1, that 30 this plate could be part of an electrical device or fixture, such as a chandelier, reading lamp or the like.

It would only be necessary in such a case to stamp out the two tongues 5 from the wall of such an electrical fixture or the like, and the receptacle members could be inserted and held as before mentioned.

What I claim is:

1. A plug receptacle comprising two like members made of insulating material, connecting means adapted to connect said members, each of said members having two lon-

gitudinal recesses extending throughout its length and a longitudinal bridge portion intermediate said longitudinal recesses, said 45 longitudinal bridge portion having lateral projections extending into said longitudinal recesses, contact springs having longitudinal portions located in passages, each of which is formed by two of said longitudinal recesses when the said members are assembled, each said contact spring having a laterally bent portion thereof bent around and under the corresponding lateral projection of the said bridge, each said contact spring having 50 a screw connected thereto underneath the respective lateral projection of the said bridge.

2. A plug receptacle comprising two like members made of insulating material, means 60 adapted to connect said members, each of said members having two longitudinal recesses extending throughout its length, the said recesses having lateral branches, a longitudinal bridge portion located intermediate the said recesses, the said bridge portion having lateral projections aligned with the lateral branches of the said recesses, contact springs having longitudinal portions located in passages, each of which is formed 65 by two of said longitudinal recesses when said members are assembled, each said spring having a laterally bent portion thereof bent around and under the corresponding lateral projection of the said bridge portion, the laterally bent portions of the said springs substantially abutting the walls of the lateral branches of the said recesses, each said contact spring having a screw connected thereto underneath the respective lateral projection 70 of the said bridge.

In testimony whereof I hereunto affix my signature.

GUSTAVE FRANKEL.
